Primary Examiner — Christian P. Mclean*Assistant Examiner* — Amber R Lee(74) Attorney, Agent, or Firm — Birchwood IP(57) CLAIM

The ornamental design for a kitchen storage rack as shown and described.

DESCRIPTION

FIG. 1 is a perspective view of a kitchen storage rack showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and

FIG. 9 is a partial enlarged view of portion 9 in FIG. 1; FIG. 10 is a partial enlarged view of portion 10 in FIG. 1; and,

FIG. 11 is a partial enlarged view of portion 11 in FIG. 2. The broken lines depict portions of the kitchen storage rack and form no part of the claimed design.

The dot dash line is included for the purpose of illustrating the bounds of the enlarged view and forms no part of the claimed design.

1 Claim, 11 Drawing Sheets(56)
